UNITED STATES PATENT OFFICE.

JAMES E. OWEN, OF EDGELEY, NORTH DAKOTA, ASSIGNOR OF ONE-THIRD TO L. C. DEVNER AND ONE-THIRD TO J. M. SILBERSTEIN, BOTH OF ST. PAUL, MINNESOTA.

WRENCH.

Application filed May 5, 1922. Serial No. 558,666.

To all whom it may concern:

Be it known that I, JAMES E. OWEN, a citizen of the United States, and resident of Edgeley, in the county of La Moure and 5 State of North Dakota, have invented a new and useful Improvement in Wrenches, of which the following is a specification.

My invention relates to wrenches and has for its object to provide a wrench having a 10 device for forcing the jaws of said wrench together to securely clamp or grip the object to be held thereby.

A still further object is to provide adjusting means for said wrench by means of 15 which the jaws of the wrench can be spread apart to any desired distance required so that the size of the object to be clamped may be varied at will and the degree of pressure applied to the same may be correspondingly varied.

In carrying out my objects I provide a shank formed at one end with a jaw and at the other end with a handle on which is 20 slidably mounted an operating head and a movable body. These two members are connected together by adjusting means and the said head is provided with a lever by means of which the same together with said head may be slid upon said shank.

30 The full objects and advantages of my invention will appear in connection with the detailed description thereof and are particularly pointed out in the claims.

In the drawings illustrating the application of my invention in one form:—

Fig. 1 is a side elevational view of my invention.

Fig. 2 is a view similar to Figure 1 showing the parts in relatively altered position, 40 some of which are shown in section.

Fig. 3 is a side elevational view of the device shown in Figure 2.

My invention consists primarily of a shank 10 to which is connected at one end a 45 fixed jaw 11 and at the other end a handle 12. Upon the shank 10, I provide a movable jaw 13 which has a guideway 14 extending through the same adapted to ride upon the shank 10. At the middle of the 50 wrench I provide a head 15 which is also formed with a guideway 16 extending through the same and which is adapted to ride upon the shank 10, similar to the jaw 13.

55 Jaw 13 and head 15 are connected to-

gether by means of a screw 17 which is screwable into a threaded socket 18 formed in jaw 13 and extending parallel to the shank 10. At the end the screw 17 is formed with an operating head 19 preferably knurled on the exterior by means of which the same may be rotated. Beyond the said head, screw 17 is provided with a reduced portion 20 which passes through a lug 21 issuing outwardly from the head 15. 60 The extreme end of portion 20 has attached to it a collar 22 by means of a pin 23 so that the screw 17 is rotatably held in place within the lug 21 by means of the head 19 and collar 22. It can readily be comprehended that as the member 19 is rotated screw 17 is caused to be screwed into or out of the jaw 13 causing the said jaw to move away from or towards the head 15 as desired.

Below the collar 22 on screw 17 and protruding outwardly from head 15 the same is formed with an ear 24. A lever 25 provided with a forked end 26 is adapted to be pivoted thereby by means of a rivet 27 to the ear 24 so that the said lever may swing from the position shown in Figure 2 to that shown in Figure 1 as required. This lever is provided with an opening 28 passing through the same in close proximity to its point of pivot to the sliding head 15. This 70 opening is formed with a cam surface 29 adapted to engage corresponding cam surface 30 on a lug 31 extending outwardly from the handle 12 of the wrench proper. These cam surfaces are so designed that when the handle 25 is positioned as shown in Figure 1 the inner corner of cam surface 29 engages the upper corner of cam surface 30. As the lever 25 and handle 12 are 75 pressed together the two cam surfaces slide along one another until they take the position shown in Figure 2 thus causing head 15 to be advanced along the shank 10 to bring jaw 13 towards jaw 11. By properly designing the cam 31 pressure can be applied to the object gripped by simply closing the lever 25. For holding the lever 25 in locked position when the object engaged by the wrench has been gripped I form the cam surface 30 with a flattened portion indicated at 32 which engages the surface 29 of lever 25 so as to hold the same from movement.

To cause the head 15 and jaw 13 attached thereto to move away from the jaw 11 when

75

lever 25 is raised I provide a device best shown in Figure 2. In this figure it will be noted that a portion of shank 10 within the head 15 is recessed as indicated at 33 to provide a space between the said head and shank. This recess provides a shoulder 34 on the shank 10. A similar shoulder 35 is formed on head 15 which is positioned opposite the shoulder 34. By placing a compression coil spring 36 within the recess 33 the same may be made to engage the shoulders 34 and 35 and to cause the head 15 to be always forced towards the lug 31. With this construction it can readily be seen that the head 15 moves away from jaw 11. When lever 25 is raised the jaws become automatically spread the maximum amount for any particular setting of the adjusting screw 17.

20 I found with my invention that the same can be made to rigidly clamp any object to be rotated so that the wrench may be used for unscrewing pipes or battered nuts and bolts to which the ordinary wrench could not be applied. In addition the wrench when once applied to the nut or pipe remains in position until the operating mechanism has been released so that the user may remove his hands from the wrench without the same becoming disengaged thereby eliminating the necessity of resetting the wrench. With the parts as arranged micrometric adjustment can be secured so that the wrench can be utilized to grip upon any surface desired. In certain instances the wrench when required can be used as a vise, the jaws being first brought together by the adjusting means and subsequently gripping by means of the clamping mechanism referred to.

30 35 40 45 50

In accordance with the patent statutes I have described the principles of operation of my invention together with the apparatus which I now consider to represent the best embodiment thereof, but I desire to have it understood that the construction shown is only illustrative and that the invention can be carried out by other means and applied to uses other than those above set forth within the scope of the following claims.

I claim:

1. A wrench comprising a shank, a fixed jaw secured thereto, a movable jaw mounted upon said shank, a movable head mounted on said shank adjacent said jaw, adjusting means positioned between said movable head and said movable jaw, a lever pivoted to said movable head, said lever having an opening extending through the same formed with a shoulder and a lug having a cam face issuing outwardly from said shank and adapted to engage said shoulder to force said head and jaw inwardly upon movement of said lever.
2. A wrench comprising a shank, a fixed jaw secured thereto, a movable jaw mounted

upon said shank, a movable head mounted on said shank adjacent said jaw, adjusting means positioned between said movable head, said adjusting means comprising a threaded spindle rotatably mounted in said movable head and screwable into said movable jaw and a lever pivoted to said head between said spindle and said shank adapted to lie flat upon said shank, said lever having an opening through the same forming a shoulder, and a lug issuing outwardly from said shank having a cam face adapted to engage said shoulder to move said movable head and movable jaw towards said fixed jaw as said lever is closed.

3. A wrench comprising a shank, a fixed jaw attached thereto, a jaw slideable upon said shank, a head slideable upon said shank, adjusting means positioned between said head and jaw, a lever pivoted to said head, means cooperating with said shank and lever for bringing the jaws together when the lever is closed.

4. A wrench comprising a shank, a fixed jaw attached thereto, a slideable jaw mounted on said shank, a slideable head mounted on said shank, adjusting means connecting said slideable head and jaw, a groove formed in said shank within said slideable head, a coil spring positioned within said groove and adapted to force said head and movable jaw away from said fixed jaw, and means for forcing said movable jaw towards said fixed jaw against the action of the coil spring.

5. A wrench comprising a shank, a fixed jaw attached thereto, a slideable jaw mounted on said shank, a slideable head mounted on said shank, adjusting means connecting said slideable head and jaw, a groove formed in said shank within said slideable head, a coil spring positioned within said groove and adapted to force said head and movable jaw away from said fixed jaw, a lever pivoted to said movable jaw and means cooperating with said lever and shank for forcing said movable jaw and movable head towards said fixed jaw upon closure of said lever.

6. A wrench comprising a shank, a fixed jaw secured thereto a handle issuing outwardly from said shank, said handle being of a width less than the width of said shank so as to form a shoulder thereon, a head slidably mounted upon said shank enveloping said shoulder and having a portion extending inwardly towards said handle to form a shoulder on said head, a coil spring positioned within said head and acting between said shoulders, a jaw connected to said head, and means for forcing said head and jaw towards said fixed jaw against the action of said spring.

7. A wrench comprising a shank, a fixed jaw secured thereto a handle issuing out-

wardly from said shank, said handle being of a width less than the width of said shank so as to form a shoulder thereon, a head slidably mounted upon said shank enveloping said shoulder and having a portion extending inwardly towards said handle to form a shoulder on said head, a coil spring positioned within said head and acting between said shoulders, a jaw connected to said head, an ear extending outwardly from said head along said handle, a lever pivoted to said ear, an opening through said

lever having a cam surface formed thereon, a lug mounted on said handle having a cam surface adapted to engage the cam surface of said lever, said surfaces being arranged to force said head inwardly towards said fixed jaw when the handle is closed, and a movable jaw attached to said head and adapted to be moved in conjunction therewith towards said fixed jaw. 15 20

In testimony whereof I affix my signature.

JAMES E. OWEN.
